UNITED STATES PATENT OFFICE.

HUGH J. MAGUIRE, OF KELLOGG, IDAHO.

ELEVATOR-BUCKET.

1,077,844.

Specification of Letters Patent.

Patented Nov. 4, 1913.

Application filed January 26, 1912, Serial No. 673,553. Renewed July 7, 1913. Serial No. 777,800.

To all whom it may concern:

Be it known that I, HUGH J. MAGUIRE, a citizen of the United States, residing at Kellogg, in the county of Shoshone, and State of Idaho, have invented new and useful Improvements in Elevator-Buckets, of which the following is a specification:

The present invention has relation to buckets designed to be attached to belts and used for elevating material and has for its object to supply a renewable lip or edge, whereby the life of the bucket is prolonged.

The invention relates more particularly to the novel form of joint between the bucket and the renewable lip or edge portion, whereby a strong and durable joint is obtained and one which will admit of the renewable portion being easily and quickly removed or placed in position.

The invention consists of the novel features, details of construction and combination of parts, which hereinafter will be more particularly set forth, illustrated in the accompanying drawing, and pointed out in the appended claims.

Referring to the drawing, forming a part of the application, Figure 1 is a perspective view of an elevator bucket embodying the invention. Fig. 2 is a perspective view of the upper portion of the bucket, a portion of the lip or renewable edge being broken away. Fig. 3 is a detail section on the line $n-x$ of Fig. 1. Fig. 4 is a detail view of a modification, showing the lip or renewable edge portion fitted to the inner side of the bucket.

Corresponding and like parts are referred to in the following description, and indicated in all the views of the drawing, by the same reference characters.

The bucket is indicated by the reference numeral 1 and may be of any construction and has the upper portion of its front and sides rabbeted, as indicated at 2. The upper portion of the back is extended above the plane of the front and sides and a space 3 is left between the upper portion of the back and the adjacent ends of the reduced edge portions of the sides formed by rabbeting the same. The spaces 3 receive the rear bent ends 4 of the lip or renewable edge portion 5. The corner portions of the bucket are flattened, as indicated at 6, and the upper reduced edge portions of the parts 6 have openings 7 to receive lugs 8

formed upon the lip or renewable edge portion 5.

The lip or renewable edge portion 5 of the bucket conforms to the outline of the upper edge portion of the bucket and may be constructed of steel, cast iron, or wrought metal and is made so as to resist wear. The lower portion of the lip or renewable edge 5 is rabbeted and the reduced portion 9 thus formed fits against the upper reduced edge portion of the front and side walls of the bucket, so that the inner and outer sides of the lip and walls of the bucket are flush, as indicated most clearly in Figs. 3 and 4. The side portions of the lip or reinforcing edge 5 are bent inwardly, as indicated at 4, and overlap the back of the bucket and are secured thereto by means of bolts 10 or like fastenings. The outer or front portion of the lip or part 5 is held to the bucket by the projections 8 fitting within the openings 7.

When the bolts or fastenings 10 are removed the bent ends 4 of the part 5 may be moved upward and after clearing the spaces 3 the lip 4 or renewable edge portion 5 may be moved outward to cause the projections 8 to clear the openings 7, after which the part 5 is entirely clear or free from the bucket. When placing the part 5 in position the projections 8 are caused to enter openings 7, after which the bent ends 4 are moved downward into the spaces 3 and are secured by the bolts or fastenings 10, which may also be utilized as means for securing the bucket to the belt or other support.

In the modification shown in Fig. 4 the lip or renewable edge 5 is fitted against the inner side of the bucket instead of against the outer side, as indicated in Figs. 2 and 3, the remaining portions being substantially the same. It is also understood that the interlocking projections 8 may be formed on either part, the other part being provided with an opening 7 to receive the projections.

The edge portion of an elevator bucket is subjected to the greatest wear and is soon worn away and instead of consigning the bucket to the scrap pile and replacing the same by a new bucket it is only necessary in accordance with this invention to replace the worn entering edge or lip by a new part, which may be effected at a nominal cost and without necessitating detachment of the

bucket from the elevator belt or like support. Moreover, the body of the bucket may be constructed of sheet metal, whereas the renewable lip or edge portion may be 5 cast or formed of steel, which may be hardened, thereby resisting wear and adding materially to the strength of the bucket which is reinforced thereby.

From the foregoing description, taken in 10 connection with the accompanying drawing, the advantages of the construction and of the method of operation will be readily apparent to those skilled in the art to which the invention appertains, and while I have 15 described the principle of operation of the invention, together with the device which I now consider to be the embodiment thereof, I desire to have it understood that the device shown is merely illustrative, and that 20 such changes may be made when desired as are within the scope of the claims appended hereto.

Having thus described the invention what is claimed as new, is:—

25 1. In combination with an elevator bucket, a renewable lip, or edge portion, therefor having a part overlapping the upper edge portion of the walls of the bucket; interlocking openings and integral projections 30 between the overlapping parts of the lip and bucket; and other means for securing the lip to the bucket.

2. In combination an elevator bucket having spaces formed between the back and the upper edge portions of the sides, a lip 35 detachably fitted to the upper portion of the bucket and having portions fitting against the upper part of the back and entering the spaces formed between said back and the upper portions of the sides, and securing means between the said lip and the bucket.

3. In combination an elevator bucket having the upper portion of its front and sides rabbeted and having spaces between the 45 back and the rabbeted portions of the sides, a renewable lip having its lower portion rabbeted to fit the rabbeted portions of the front and sides of the bucket and having its end portions bent and fitted against the 50 upper part of the back and entering the spaces formed between said back and the rabbeted portions of the sides of the bucket. interlocking openings and integral projections between the front portion of the lip and the bucket, and securing means between the back of the bucket and the overlapping parts of the lip.

In testimony whereof I affix my signature in presence of two witnesses.

HUGH J. MAGUIRE.
